(57) **CLAIM**

The ornamental design for a cap, as shown and described.

DESCRIPTION

FIG. 1 is a top isometric view of a cap;

FIG. 2 is a top plan view of the cap of FIG. 1;

FIG. 3 is a bottom plan view of the cap of FIG. 1;

FIG. 4 is a right elevational view of the cap of FIG. 1, the left elevational view being identical to the right elevational view; and,

FIG. 5 is a front elevational view of the cap of FIG. 1, the rear elevational view being identical to the front elevational view.

The broken lines shown in the drawings indicate structure and features which form no part of the claimed design.
